UNITED STATES PATENT OFFICE.

DAVID MOLINE LÓPEZ, OF CLARKSDALE, ARIZONA.

PHOTOGRAPHIC-PRINTING MACHINE.

Application filed July 25, 1921. Serial No. 487,389.

To all whom it may concern:

Be it known that I, DAVID M. LÓPEZ, a citizen of the United States, residing at Clarksdale, in the county of Yavapai and 5 State of Arizona, have invented certain new and useful Improvements in Photographic-Printing Machines, of which the following is a specification.

This invention relates to photographic printing machines, and the primary object of the invention is to provide a machine of simple and durable construction, which will permit the printing of photographs, from either films or plates, in a convenient and ex- 15 peditious manner.

Another object of the invention is to provide an improved photographic printing machine embodying a casing having printing lights arranged therein, a hinged platen, 20 means carried by the hinged platen for urging the printing paper into engagement with the negative, and means for manually controlling the circuits to the printing lights, and means for automatically closing the cir- 25 cuits to the printing lights, when the platen is swung to its operative position.

A further object of the invention is the provision of a pair of adjustable printing lights arranged in the casing, a novel means 30 for independently adjusting the lights according to the nature of the films from which the pictures are being printed, a dark room lamp arranged in the casing, and means for automatically opening the circuit to the dark 35 room lamp, and closing the circuit through the printing lamps, when the hinged platen is swung to its operative position; said automatic means closing the circuit to the dark room lamp and opening the circuit to 40 the printing lamps, when the platen is swung to its open or inoperative position.

A still further object of the invention is the provision of a novel mask carried by the printing glass, arranged at the upper end 45 of the casing, which is so constructed as to permit all sizes of films to be readily and easily accommodated in a minimum amount of time.

With these and other objects in view, the 50 invention consists in the novel construction, arrangement and formation of parts, as will be hereinafter more specifically described, claimed and illustrated in the accompanying drawings, forming a part of this specification, in which drawing:

Figure 1 is a top plan view of the im-

proved printing machine, showing the platen swung back to its open inoperative position.

Figure 2 is a transverse vertical section 60 through the improved machine, taken on the line 2—2 of Figure 3.

Figure 3 is a vertical longitudinal section, taken on the line 3—3 of Figure 2.

Figure 4 is a fragmentary detail perspective view of the mask, showing the means for slidably connecting the sections there- 65 of together.

Figure 5 is a fragmentary detail per- 70 spective view of a portion of the platen, illustrating the means of resiliently connect- ing the paper engaging part with the frame of the platen.

Figure 6 is a diagrammatic view of the 75 wiring circuit for the printing and dark room lamps.

Referring to the drawings in detail, wherein similar reference characters designate corresponding parts throughout the several views, the letter A indicates the cas- 80 ing of the improved machine; B, the platen therefor; C, the dark room lamp; D, the printing lamps; E, the means for adjusting the printing lamps; F, the automatic means for controlling the circuit to the 85 printing lamps and dark room lamp; and G the novel type of mask utilized with the improved printing machine.

The casing A may be of any desired size, and formed of any desired material. As 90 shown, the casing is formed of wood and includes the front wall 10, the rear wall 11, the end walls 12 and 13, and the bottom wall 14.

The upper end of the casing A is left open 95 and is adapted to be closed by the hinged platen B, which will be hereinafter more fully described. The upper edges of the front, rear and side walls, 10, 11, 12 and 13 are rabbeted as at 15, for the reception of 100 the printing glass 16. If so desired, a suitable felt or other pad 17 may be fitted in the rabbeted portion 15, in order to form a seat for the printing glass.

The rear wall 11 is provided with a longitudinally extending slot 18, which defines a guide way for the printing lamps D, which as stated, will be hereinafter more fully described.

The mask G is arranged on the upper sur- 110 face of the printing glass 16, and includes the two sections 20 and 21. Each section in-

cludes a pair of right angularly extending legs 22 and 23. The legs 22 are formed relatively longer than the legs 23 and extend longitudinally of the casing, while the legs 23 extend transversely of the casing. The legs 22 and 23 of the sections 20 are slotted longitudinally as at 25, to provide the upper struck guide ways 26, which are adapted to receive the legs 22 and 23 of the section 21. 10 This permits the convenient adjusting of the sections 20 and 21 in relation to each other, to form different sized openings, according to the size of the negatives from which the prints are to be made. In order to facilitate 15 the setting of the mask to different sized prints, the legs 22 and 23 of the section 20 are graduated, as at 27.

The platen B includes the open frame 30 and the solid print engaging plate 35. The 20 frame 30 includes the front and rear bars 31 and 32, and the side bars 33. The frame is also braced by bracing strips 34, which may also act as handles for raising and lowering the platen, if so desired. The rear bar 32 25 extends rearwardly of the casing A, and is connected to the casing A by means of hinges 36, which are secured to the rearwardly extending strip 37, carried by the rear wall 11 at the upper edge thereof. The front strip 31 is adapted to be engaged by a hinged catch 38, which is carried by the front wall 10, and serves as means to hold the platen in its lowered operative position. One end bar 33 is extended laterally of one end of the casing, and forms means for operating the automatic switch structure F for controlling the lighting of the dark room lamp C and the printing lamps D. The longitudinal bars 31 and 32 have secured to their inner faces 40 guide tracks 40, which receive the free terminals of the bow springs 41 which are pivoted intermediate their ends as at 42 to the outer surface of the plate 35. These springs 41 normally tend to urge the plate 35 downwardly into forcible contact with the printing paper to hold the same against the printing glass 16. It can be seen that the plate 35 is of such size as to permit the same to slide in the frame 30.

50 The dark room light C may be an ordinary incandescent bulb of a red or similar color, and has the base 44 thereof, secured to the rear wall 11 of the casing, adjacent to the lower end thereof. This lamp C is arranged substantially at the transverse center of the casing.

55 The printing lamps D may also be of the ordinary incandescent type and of any desired candle power, and as shown two of these lamps have been provided, and are designated by the numerals 45 and 46. The printing lamps 45 and 46 are detachably secured to bases 47, which are mounted in the slot 18 formed in the rear wall 11. The rear 60 wall 11 has secured to its outer face, a guide

way 49, and this guide way has slidably mounted therein plates 48, to which are secured the lamp bases 47. This permits the convenient sliding of the lamps 45 and 46 toward each other, for a purpose which will be hereinafter more fully described. The means E for adjusting the lamps 45 and 46 consists of a sliding and rotatable rod 50. This rod is extended into the guideway 49 and is mounted for free sliding and rotary movement in a bore 51 formed in the base plate 48 of the lamp 46. The inner end of the rod is provided with a screw threaded terminal 52, which is fitted into a threaded bore 53, formed in the plate 48 of the lamp 45. The rod 50 on each side of the plate 48 of the lamp 46 and in spaced relation thereto is provided with pins 54, and when it is desired to adjust the lamps, it can be seen that the rod 50 can be slid inwardly or outwardly and movement will be first imparted to the lamp 45, and then to the lamp 46. By turning the rod 50, it can be seen that the same can be threaded into or out of the bore 53, and thus permit of independent movement 90 of the lamp 45. These lamps are adjustable, so that the same can move from one end of the casing to the other, so that if the film is darker or denser at one portion than at another, the lamps can be adjusted toward 95 this portion.

It is also desirable that the lamps be independently controlled, that is the circuits thereof be independently controlled, so that in case only one light is needed, the other light can be put out. In actual use, only one light will be necessary, but in real dark or dense films, two lamps can be used.

The automatic switch structure F for controlling the opening and closing of the circuit to the dark room lamp C and the printing lamps D, consists of a vertical reciprocating rod 60. This rod 60 is mounted in suitable guide members 61 carried by the end wall 13. The lower or inner end of the rod 60 has secured thereto a plate 62, which carries a conducting plate 63. This conducting plate 63 may be inserted or arranged on a suitable insulating block 64, carried by the plate 62. The conducting plate 63 has secured thereto one line wire 65, while the other line wire 66 is extended into the casing and connected to one terminal of the dark room lamp C. The other terminal of the dark room lamp C has secured thereto the electric wire 67, which has the outer end thereof bared and extended through the side wall 13, as at 68, in order to form a contact, as clearly shown in Figures 3 and 6. One terminal of the lamps B are connected to a conductor wire 69, which has its outer terminal left bare and extended through the wall 13 of the casing to form a contact 70. The contacts 68 and 70 are arranged in spaced relation to one another and can be 120 125 130

fitted in suitable insulating sleeves 71, carried by the side wall 13 of the casing. As shown, these contacts are extended into the guide housing 72 formed for the lower end 5 of the rod 60, and the plate 62 is adapted to slide in this guide housing. The wire 65 is also extended through the side wall 13 of the casing and is secured directly to the plate 63 as heretobefore described. The 10 lamp 45 has connected to its other terminal a wire 75, which is connected to the line wire 66. The lamp 46 has connected to its other terminal a wire 76, which is also connected to the line wire 66. These wires 75 15 and 76 have interposed therein suitable hand or other manually operated switches 77 and 78, respectively. As clearly shown in Figures 1 and 3 of the drawings, these switches 77 and 78 are carried by the rear wall 11 of 20 the casing, and extend outwardly therefrom. It can be seen that by operating the switches 77 and 78, the lighting of the lamps can be manually controlled.

The rod 60 is normally urged upwardly 25 by means of a spring 79, which is coiled around the same. The spring engages the upper end of the housing 72 and against a pin 80 carried by the rod. When the platen B is in its raised position, the rod 60 is in 30 its raised position owing to the influence of the spring 79 acting upon the same, and the conducting plate 63 will be in engagement with the contact 68, thus closing the circuit to the dark room lamp C. It can be seen 35 that the dark room lamp C is normally in circuit when the platen is raised, so that the printer can readily see to place the negative and the printing paper on the printing glass plate 16. The front wall 10 of the casing 40 may be provided with suitable red and orange colored glasses 81 and 82, so that the machine can be used for dark room work, when so desired.

In operation of the improved machine, 45 the platen B is first moved to its open position and the mask G is adjusted to the size of the negative from which the prints are to be made. The negative is then placed in position on the glass plate 16 and the printing paper placed over the same. The platen B is then swung downwardly, and the hook 38 moved over the forward strip 31 thereof. This will urge the plate 35 into tight engagement with the printing paper and make 50 good contact between the negative printing paper and printing glass 16. If so desired, the lower surface of the plate 35 may be provided with a felt pad 35'. Upon lowering of the platen B, one end strip 33 will engage 55 the upper end of the rod 60 and move the same downwardly against the tension of the spring 79. This will move the contact plate 63 from out of engagement with the contact 68, and into engagement with the 60 contact 70, thus closing the circuit through

the lamps 45 and 46. When the rod is in its lower position, it can be seen that current will flow through the line wire 65, through the plate 63, through the wire 65, through the lamps 45 and 46, through the wires 75 70 and 76, through the switches 77 and 78, and then through the line wire 67. Before the printing operation, however, the lamps 45 and 46 can be adjusted according to the nature of the negative as heretobefore 75 stated, and either one or both of the lamps may be used.

From the foregoing description, it can be seen that an improved printing machine has been provided of exceptionally simple and 80 durable construction, which will permit the easy and convenient printing from films and plates.

Changes in details may be made without departing from the spirit or scope of this invention; but,

I claim:

1. A photographic printing machine comprising a casing, a printing lamp in the upper end of the casing, a hinged platen 90 for the casing, a pair of printing lamps arranged in the casing, a dark room lamp, circuits for the printing lamps and the dark room lamp including a pair of line wires, the dark room lamp being interposed in one 95 of the line wires, an automatically operated switch carried by one side wall of the casing, means normally urging the switch to a raised position, a contact plate carried by the switch, means electrically connecting the 100 other line wire to the contact plate, a lead wire, means electrically connecting one terminal of each lamp to the lead wire, lead wires secured to the other terminals of the print lamps and connected to the 105 first mentioned line wire, and contact points formed on the first mentioned lead wire and the first mentioned line wire and arranged in the path of said contact plate, and a bar carried by the hinged platen and arranged 110 in the path of said sliding rod.

2. A photographic printing machine comprising a casing, a printing glass carried by the upper end of the casing, a hinged platen carried by the casing including a frame, and 115 a plate slidably carried by the frame, resilient leaf springs pivotally secured intermediate their ends to the platen, and guide tracks carried by the frame arranged to detachably receive the free terminals of said leaf 120 springs.

3. A photographic printing machine comprising a casing, a pair of independent printing lamps slidably mounted in the casing, a dark room lamp, colored transparent glasses carried by the front wall of the casing, a guide track carried by the rear wall of the casing, base plates secured to each one of said printing lamps 125 slidably mounted in said guide track and an 130

adjusting rod arranged in said guide track and operatively connected to said base plates.

4. A photographic printing machine comprising a casing, a guide slot carried by one wall of the casing, independent printing lamps slidably mounted in the guide slot, and means operatively connected to said lamps for adjusting the same within the guide slot.

10. 5. A photographic printing machine comprising a casing, a mask supported at the upper end of the casing, said mask being formed in sections, each section including a pair of right angularly suspending legs, one 15 of said legs being longer than the other, the

legs of one section having longitudinal slots to provide upstruck guideways adapted to receive the leg portions of the other sections whereby to permit of adjustment of the two sections.

6. A photographic printing machine comprising a casing, a pair of independent printing lamps slidably mounted in the casing, a guide track carried by one wall of the casing, base plates secured to said printing lamp and slidably mounted within said guide track and means operatively connecting said base plate to provide for adjustment of the lamp within the casing.

DAVID MOLINE LÓPEZ.
